DESIGN FOR A HOBBYHORSE

George Earl Montague, Venice, and Robert C.
Romero, Los Angeles, Calif.

Application December 26, 1944, Serial No. 117,084

Term of patent 3½ years

(Cl. D34—15)

To all whom it may concern:

Be it known that we, George Earl Montague and Robert C. Romero, citizens of the United States and Mexico, respectively, and residing respectively at Venice and Los Angeles, in the county of Los Angeles, State of California, have invented a new, original, and ornamental Design for Hobbyhorse, of which the following is a specification, reference being had to the accompanying drawing, forming part thereof, in which:

Fig. 1 is a perspective view of the hobbyhorse

as seen from the front and one side thereof showing our new design;

Fig. 2 is a perspective view of the hobbyhorse as seen from the rear thereof and showing the side opposite that shown in Fig. 1.

We claim:

The ornamental design for a hobbyhorse, substantially as shown.

GEORGE EARL MONTAGUE.
ROBERT C. ROMERO.
